COMBINED BRACKET AND BLOWER FOR BROILERS AND THE LIKE

Alexander P. Delaney, Phoenix, N.Y., assignor of one-third each to Ray L. Carter and Walter G. Stone, both of Phoenix, N.Y.

Filed Jan. 2, 1964, Ser. No. 78,019

Term of patent 7 years

(Cl. D62—2)

FIGURE 1 is a front elevation of a combined bracket and blower for broilers and the like showing my new design;

I claim:

The ornamental design for a combined bracket and blower for broilers and the like, as shown.
